UNITED STATES PATENT OFFICE

2,078,821

VARIABLE CONTROL MECHANISM

Charles Walker, Knoxville, Tenn.

Application August 24, 1935, Serial No. 37,738

7 Claims. (CL. 74—125.5)

My invention consists in new and useful improvements in a variable transmission mechanism particularly adapted for use in connection with the registering device of a liquid dispensing pump or the like, whereby the price per gallon, the total volume of liquid, and the total cost of the liquid dispensed, are indicated.

The primary object of my invention is to provide a transmission mechanism of this character whereby the rotary movement of a driving member will be transmitted into a different rate of speed of a driven member, without in any way affecting the speed of rotation of said driving member.

Another object of my invention is to provide a flanged transmission disc rotatable by a retractable pawl member, the degree of rotation of said disc being dependent upon the duration of its engagement by said pawl.

A further object is to provide a pivoted pawl member, one arm of the latter being engageable by a variable contact surface for selectively controlling the extent of engagement of said pawl with said flanged disc.

A still further object is to provide mechanism operable by the pawl member for positively arresting the rotation of said transmission disc.

With the above and other objects in view which will appear as the description proceeds, my invention resides in the novel features herein set forth, illustrated in the accompanying drawings and more particularly pointed out in the appended claims.

Referring to the drawings in which numerals of like character designate similar parts throughout the several views,

Fig. 1 is a view in front elevation, partly broken away, showing a liquid dispensing pump of the gasoline filling station type.

Fig. 2 is a sectional view taken on line 2—2 of Fig. 1.

Fig. 3 is a diagrammatic view of the disc and gearing of Fig. 2, looking from the right.

Fig. 4 is an enlarged view in side elevation of the transmission disc and operating mechanism.

Fig. 5 is a sectional view taken on line 5—5 of Fig. 4.

Fig. 6 is a fragmentary view similar to Fig. 4, showing the control member of the transmission mechanism in a different position.

Fig. 7 is a fragmentary view similar to Fig. 6, but showing the stop means for the transmission mechanism.

Fig. 8 is a sectional view taken on line 8—8 of Fig. 7.

Fig. 9 is an enlarged view similar to Fig. 7 but showing the stop mechanism in inoperative position.

Fig. 10 is a similar view showing the stop mechanism in operative position.

Fig. 11 is an enlarged detail section of one of the registering dials, and

Fig. 12 is a modified view of stop means for the transmission mechanism.

In the drawings, 1 represents the housing of a conventional gasoline pump within which is located a pump proper 3 connected by pipe 4 to a gasoline supply tank, not shown. The pump is operated by an electric motor 2 through the medium of a train of gears 5, 6 and 7, to force the gasoline up through pipe 8 into a meter 9 and out through discharge pipe 10. From this pipe 10, the gasoline is conducted through pipe 11, pipe 14 into sight gauge 13, from whence it is discharged through the hose 15 and out through the nozzle 17. As shown in Fig. 1, the nozzle 17 is provided with the conventional valve 16 actuated by valve handle or lever 18, the latter being protected by a guard member adapted to cooperate with a hook 19 pivotally mounted on the side wall 25 of the casing 1, for holding the nozzle and hose in position when not in use.

The meter 9 is provided with suitable mechanism, the specific structure of which forms no part of my invention, whereby the passage of fluid therethrough rotates a vertical shaft, the extent of rotation of the latter being commensurate with the volume of fluid being pumped. The outer end of this vertical shaft carries a pinion 20 adapted to mesh with a second pinion 21 keyed to the lower end of a vertical shaft 22 suitably supported in bearings on a bracket 22a, mounted in the casing 1, as clearly shown in Fig. 2. The upper end of the shaft 22 carries a bevel gear 23 adapted to mesh with a second bevel gear 24 on a longitudinally extending shaft 37, mounted in bearings 38 and 39 in the side walls of the casing.

Adjacent the bevel gear 24, the shaft 37 carries a gear 25 adapted to mesh with an intermediate gear 26 mounted on a short shaft carried by 45 the bracket 22a, said intermediate gear meshing with gear 27 freely mounted on a hollow shaft 38 adjacent the volume register dials 251. Gears 28 and 29 are also freely rotatable on shaft 38 and are operatively connected to the total cost 50 register dials 241 and the price setting dials 231, respectively.

34 designates a gear carried by the hub portion of a flanged transmission disc 40 freely rotatable on shaft 37 and adapted to mesh with 55

intermediate gear 30 mounted on a second short shaft carried by bracket 22a, said intermediate gear 30 meshing with gear 28 of the cost dials 241.

As shown in Figs. 4 and 5, the inner periphery 5 of the flange of disc 40 is provided with a series 10 of internal teeth 58 engageable by one end 49 of a pawl member pivotally mounted on a transverse pin 48 on a co-axial disc 47 which is keyed 15 to shaft 37. The pawl end 49 is normally held 20 in engagement with the teeth 58 by means of a spring 52 also secured to the disc 47 as at 53. The other end 51 of the pawl member terminates 25 in a pin or projection 51a (Fig. 6) for the purpose hereinafter set forth.

15 Adjacent the keyed disc 47 and co-axial therewith is a stationary circular plate 45 supported by bracket 54 on the casing 1, the periphery of said plate being provided with a channel groove 46 which terminates in a spiral portion gradually receding axially from the periphery of said 25 plate. 65 designates a linked flexible chain slideable within the groove and capable of completely encircling the periphery of the plate 45 to form a contact surface for the pin 51a on the 30 end 51 of the pawl member, to rock the pawl end 49 thereof out of engagement with the teeth 58 on the inner periphery of the flanged disc 40.

It will thus be seen that when the chain 65 completely encircles the periphery of the plate 45, 35 the end 49 of the pawl will remain out of engagement with the teeth 58, so that when the motor 2 is started, the disc 47 and carried pawl will rotate with the shaft 37 without rotating disc 40. However, by retracting the chain in the 40 groove, the distance between the point of emergence and the outer end 71 of said chain may be regulated to control the extent of engagement of said pawl with the teeth on disc 40 to rotate the latter.

40 The outer end 71 of chain 65 is connected to an arm 43 (Figs. 4 and 5) by means of a transverse pin 44, the arm 43 being keyed to a hub 42 of gear 35 freely rotatable on shaft 37, and co-axial with the arm 43 and plate 45. Gear 35 45 meshes with a pinion gear 34 carried by the shaft of a gear 33, which latter gear meshes with gear 29 of the price setting dials 231, as clearly shown in Figs. 2 and 3. The price setting dial is regulated by a gear 32 operated by handle H, and 50 simultaneously with the setting of this dial, the chain 65 is either retracted within the spiral groove in plate 45, or protracted, to regulate the extent of engagement of the pawl 49 with the teeth on the flanged disc 40.

55 In order to prevent overrunning of the flanged disc 40, I provide a stop mechanism (Figs. 7, 8, 9 and 10) comprising a plate member 66 mounted on the end of the arm 43 by means of the chain-engaging pin 64' and a second pin or bolt 70. 60 Carried by this plate member 66 is a projecting pin or plunger 68 beveled at its outer end to engage the teeth on the inner periphery of the flanged disc 40, the other end of said plunger being enlarged to provide an abutment face 68a for 65 engagement by the projecting end 51a of the pawl member. The plunger 68 is normally forced out of engagement with the teeth 58 by means of a coil spring 69 suitably retained in a spring chamber formed within a housing 67 carried by the 70 plate member 66, whereby when the pawl 49 is in engaging position with the teeth 58, the stop pin 68 will be forced inwardly by the spring 69 out of engagement with said teeth. However, immediately upon the disengagement of the pawl 75 49, its other end 51a will be interposed between

the abutment 68a of stop pin 68, and the periphery of the chain, to momentarily force the stop pin 68 outwardly against the teeth 58 to arrest the rotation of the disc.

5 The stop mechanism illustrated in Fig. 12 comprises an electro-magnet 84 having an armature 83 carried at one end of a lever pivotally mounted at 82, said armature being normally held out of engagement with the magnet by means of a spring 85. 80 represents a friction brake connected to the other end of the lever at 81 and adapted to frictionally engage the outer edge of the flange on disc 40. Any suitable electric circuit (not shown) may be connected to the end 85 of the pawl and the end 71 of the chain 65, 15 whereby when said members contact, the electromagnet will be energized to rock the armature 83 and force the brake 80 into frictional engagement with the flange on the disc 40 to stop the latter. 20

As shown in Fig. 11, the hollow shaft 36 is adapted to receive a longitudinally extending rod 62, one end of which projects outwardly through one wall of the casing 1 in abutting engagement with the hook 19 (Fig. 1), its inner end co-operating with a spring 64 to normally force said rod outwardly. Adjacent the total cost register 241, the rod carries a transverse pin 60 lying in longitudinal slots 61 and cooperating with a circular channel 58 provided in the annular face 30 of a spur gear 59 freely rotatable on shaft 36.

When the nozzle 17 is in place on the hook 19, the rod 62 is forced inwardly against the spring 64, and the spur gear 59 occupies the position shown in Fig. 11, lying completely within the 35 confines of an annular recess in the gear 28 and meshing with a series of internal teeth provided within said recess. Upon the removal of the nozzle from the hook 19, spring 64 moves the rod 62 toward the left, permitting spur gear 59 to be 40 moved with it through the medium of the pin 60, to slip into the internal teeth 57 provided in the annular recess of the adjacent dial on the cost register 241.

The depth of the recess in the dial of the 45 register 241 is less than the transverse width of the spur gear 59, whereby the latter will be meshing with the teeth 57 simultaneously with the teeth 56 in the gear 28. However, the depth of the recess in the gear 28 is at least equal to the 50 transverse width of the spur gear 59, so that when the nozzle is in place on the hook 19, and the rod is forced to its extreme position to the right, the spur 59 will only be in engagement with the teeth 56, thereby permitting the dials of register 55 241 to be returned to normal zero position by means of the spring 63.

The construction of the volume register 251 is 55 similar in all respects to register 241 just described, and a detail explanation of the former is believed unnecessary.

Having thus described the construction of my improved device, its operation is as follows:

Assuming that the price of gasoline is 18.76 per gallon but that the dials 251, 241 and 231 all 60 register zero, the chain 65 in this instance will completely encircle the plate disc 45, thus holding the pawl 49 out of engagement with the teeth 58 on the flanged disc 40.

The handle H is turned in a clockwise direction 65 until the price dials 231 register 18.7. Simultaneously with the setting of this price dial, the flexible chain 65 will be retracted in the spiral groove 46 a predetermined extent, through the 70 medium of the arm 43 on hub 42 and the inter- 75

connected gears 35, 34, 33, 29 and 32, leaving a predetermined space or gap between the point of emergence of the chain from the groove, and its outer end.

5 The nozzle is then removed from the hook 19, permitting the rod 62 to be forced outwardly to the left by means of the spring 64, to cause the spur gears 59 meshing with the teeth 56, to also engage the teeth 51 on the register dials 241 and 251. The motor is started to operate the pumping mechanism, and through the medium of the vertical shaft 22 and bevel gears 23 and 24, the shaft 37 together with its keyed disc 47 are rotated in a counterclockwise direction (Figs. 4, 15 5 and 6). The pivoted pawl member carried by the disc 47 will rotate with the latter, causing its projecting end 51a to fall onto the periphery of the plate disc 45 and permitting its other end 49 to engage a tooth 50 on the flange disc 40 to rotate the latter. Upon reaching the outer 20 end 71 of the chain 65, the projecting end 51a of the pawl will be lifted onto the chain 65 to rock the pawl end 49 out of engagement with the teeth 50. Simultaneously with this rocking of the 25 pawl member, its end 51a will be interposed between the stop pin 68 and the end 71 of the chain to momentarily force said pin into braking engagement with a tooth 50 on the flanged disc 40, to prevent further rotation of said disc.

30 As the disc 47 continues to rotate with the shaft 37, the arm 51 of the pawl will again clear the stop pin 68 and continue to ride on the chain 65 until it reaches the point of emergence of the chain, when it is again forced down onto the periphery of the plate disc 45 by the spring 52, to cause pawl 49 to again engage a tooth 50 on the disc 40 to rotate the latter.

The volume register 251 will rotate with the shaft 37 through the medium of the gears 25, 26 40 and 27, and the cost register 241 will be rotated with the flanged disc 40 by means of the gears 31, 30 and 28.

The above operation is repeated until the total volume of gasoline desired has been dispensed, 45 when the motor is stopped and the nozzle 17 is placed on the hook 19, forcing the rod 62 inwardly and permitting the registers 251 and 241 to return to their normal zero position by means of their respective springs 63.

50 It will be seen that with my arrangement of a retractable flexible chain forming a variable contact surface for the pawl member, to selectively control its engagement with the teeth 50 of the flanged disc 40, I am enabled to provide a transmission mechanism for the cost register of a filling station pump which may be varied to accommodate a wide range of prices of the gasoline dispensed.

From the foregoing it is believed that the construction and advantages of my invention may be readily understood by those skilled in the art without further description, it being borne in mind that numerous changes may be made in the details disclosed without departing from the 65 spirit of my invention as set out in the following claims.

What I claim and desire to secure by Letters Patent is:—

1. A variable control mechanism comprising a 70 rotary shaft, means for driving said shaft, a disc keyed to said shaft and rotatable therewith, a flanged transmission disc immediately adjacent said rotatable disc and freely rotatable on said shaft, with its flange overlying the periphery of 75 said rotatable disc, a predetermined number of

internal notches in said flange, a pivoted pawl carried by said rotatable disc, spring means normally tending to force one end of said pawl into engagement with said notches, a fixed circular plate co-axial with said discs and provided with a 5 peripheral groove which terminates in a spiral portion which recedes from said periphery, a flexible band slidable in said groove and capable of completely encircling the periphery of said plate to form a contact surface from the other end of 10 said pawl, and means for selectively positioning said flexible band to vary the extent of surface contact for said pawl.

2. A variable control mechanism comprising a rotary shaft, means for driving said shaft, a 15 disc keyed to said shaft and rotatable therewith, a flanged transmission disc immediately adjacent said rotatable disc and freely rotatable on said shaft, with its flange overlying the periphery of 20 said rotatable disc, a predetermined number of internal notches in said flange, a pivoted pawl carried by said rotatable disc, means normally tending to force one end of said pawl into engagement with said notches, a fixed circular plate co-axial with said discs, a retractable band capable of completely encircling the periphery of 25 said plate to form a variable contact surface for the other end of said pawl, and means for selectively retracting said band.

3. A variable control mechanism comprising a 30 rotary shaft, means for driving said shaft, a disc keyed to said shaft and rotatable therewith, a flanged transmission disc immediately adjacent 35 said rotatable disc and freely rotatable on said shaft, with its flange overlying the periphery of said rotatable disc, a predetermined number of internal notches in said flange, a pivoted pawl carried by said rotatable disc, spring means normally tending to force one end of said pawl into engagement with said notches, a fixed circular 40 plate co-axial with said discs and provided with a peripheral groove which terminates in a spiral portion which recedes from said periphery, a flexible band slidable in said groove and capable of completely encircling the periphery of said plate 45 to form a contact surface for the other end of said pawl, means for selectively positioning said flexible band to vary the extent of surface contact for said pawl, and means actuated by said pawl for positively arresting the rotation of said 50 transmission disc upon its release from said rotatable disc.

4. A variable control mechanism comprising a 55 rotary shaft, means for driving said shaft, a disc keyed to said shaft and rotatable therewith, a flanged transmission disc immediately adjacent said rotatable disc and freely rotatable on said shaft, with its flange overlying the periphery of 60 said rotatable disc, a predetermined number of internal notches in said flange, a pivoted pawl carried by said rotatable disc, spring means normally tending to force one end of said pawl into engagement with said notches, a fixed circular plate co-axial with said discs and provided with a 65 peripheral groove which terminates in a spiral portion which recedes from said periphery, a flexible band slidable in said groove and capable of completely encircling the periphery of said plate to form a contact surface for the other end 70 of said pawl, a rotary arm co-axial with said discs and connected to one end of said band, and means for rotating said arm to selectively vary the contact surface for said pawl.

5. A variable control mechanism comprising 75

a rotary shaft, means for driving said shaft, a disc keyed to said shaft and rotatable therewith, a flanged transmission disc immediately adjacent said rotatable disc and freely rotatable on said shaft, with its flange overlying the periphery of said rotatable disc, a predetermined number of internal notches in said flange, a pivoted pawl carried by said rotatable disc, spring means normally tending to force one end of said pawl into engagement with said notches, a fixed circular plate co-axial with said discs and provided with a peripheral groove which terminates in a spiral portion which recedes from said periphery, a flexible band slideable in said groove and capable of completely encircling the periphery of said plate to form a contact surface for the other end of said pawl, a rotary arm co-axial with said discs and connected to one end of said band, and means whereby the rotation of said arm in one direction retracts said band in said spiral groove and rotation in the other direction protracts the

same, for varying the pawl engaging surface of said band.

6. Apparatus as claimed in claim 5 including means actuated by said pawl for positively arresting the rotation of said transmission disc 5 upon its release from said rotatable disc.

7. A variable control mechanism comprising a rotary shaft, means for driving said shaft, a disc keyed to said shaft and rotatable therewith, a transmission disc immediately adjacent said 10 rotatable disc and freely rotatable on said shaft, a fixed circular plate co-axial with said discs, clutch means on said rotatable disc, interposed between said fixed plate and said transmission disc for operating the latter, a retractable band 15 capable of completely encircling the periphery of said fixed plate, to control the engagement of said clutch means with said transmission disc, and means for selectively retracting said band to vary the extent of engagement of said clutch 20 means.

CHARLES WALKER.
